UNITED STATES PATENT OFFICE

DAVID B. REESE, OF ST. PAUL, MINNESOTA

SANITARY FROSTPROOF COLLAR

Application filed August 16, 1927. Serial No. 213,308.

My invention relates to sanitary frost proof collars particularly adapted to ice cream cabinets used in soda fountains where ice cream is kept in the cans which are placed in the cabinets associated with the fountain.

A feature of my invention resides in a collar having an insulating body portion so that the cold on one side of the same from the cabinet will not extend to the other side. This provides a means for keeping the outer surface of the collar against collecting frost by reason of the warm air on one side and the cold air from the cabinet on the other side.

My invention includes a sanitary replaceable covering and my cover is made of paper or other suitable material. The paper cover may be paraffined or treated in a manner so as to be virtually moisture proof.

It is a feature of my invention to provide a collar for ice cream cabinets having a means to level off the disher or scoop which is used in filling cones. This may be in the form of a projecting portion in one side of the collar or it may form a part thereof which is adapted to extend annularly about inside of the collar and depend in the same.

These features together with other details and objects of my invention will be more fully and clearly set forth in the specification and claims.

In the drawings forming part of this specification:

Figure 1 is a perspective view of my collar as it would appear in use, a portion of which is broken away.

Figure 2 is a perspective view of my sanitary frost proof collar.

Figure 3 is a plan view of the same. Figure 4 illustrates the sanitary liner removed from the collar and as it would appear in its dried out formation.

Figure 5 illustrates another form of my sanitary frost proof collar, a portion of which is broken away.

Figure 6 shows the collar illustrated in Figure 5 as it would appear in use in the cabinet and a portion of the same broken away.

Figure 7 illustrates the sanitary removable

collar as it would appear when folded ready to be inserted into the frost proof collar.

Figure 8 is a perspective view of another form of my collar as it would appear in use in the cabinet and a portion of the same being broken away.

Figure 9 is a plan view of an alternative form of my collar.

My sanitary frost proof collar A is adapted to be used with a cabinet B, only a portion of which is illustrated in the drawings, having a top portion 10 which extends over the ice C of the cabinet B.

The cabinets B are made ordinarily to be used with soda fountains and are provided with several openings 11 in the top portion 10 so that ice cream cans D may be placed in the cabinets and the ice C packed around these cans. This keeps the ice cream cold and froze in the cabinet B. A suitable cover 12 for closing the openings 11 such as 12 which is partially illustrated in Figure 6 is used to close the opening 11 in the top 10 of the cabinet B.

The opening 11 is ordinarily quite a bit larger than the diameter of the can D so that a space between the top of the can and the opening 11 is apparent and in this space ice cream is spilled ordinarily in using these cases B, making a very undesirable condition in these cabinets and cases. My invention is designed to overcome this and to provide a sanitary frost proof collar A which is adapted to fit over the can D and rest against the bead 13 formed near the top edge of the can D.

The collar A is formed with a top bead 14 and is provided with an outer wall 15 and an inner wall 16. The outer and inner walls 15 and 16 are joined together by the straight band portion 17 so as to provide a dead air space 18 between the walls 15 and 16.

The band 17 fits over the neck of the can D and down to the shoulder 13. This holds the collar A so that the flaring side walls 15 and 16 extend to fill the space between the can D and the diameter of the opening 11.

The band portion 17 is formed with a lip 20 which extends upward from the main body portion of the band and then is bent

to extend downward with the cutting portion 21 along the lower edge of the lip which is adapted to be used as a scraper for leveling off the disher used for filling cones. 5 In this manner I provide a means associated with my collar which assists the merchant in dishing out ice cream from the cans D and provides a scraper or leveling means which permits the dealer to more easily place the 10 ice cream into the cone because of the uniform size and shape of the ice cream dished out by the disher and preventing the edges which are ordinarily ragged where a scraper is not used from sticking out over the edge 15 of the cone when the ice cream is placed in the same.

I provide a sanitary cover member E for my collar A which is adapted to be folded so as to fit into the flare of the collar A and 20 rest against the wall 16. This cover E keeps the walls 16 of the collar A clean and if any of the ice cream is dropped onto the cover E it can be easily wiped off or the cover may be replaced by a new, clean cover, therefore 25 by keeping the opening about the can D clean and sanitary at all times. My cover E is particularly desirable where ice cream is being dished out frequently from the can D and flavoring or other material is apt to 30 be dropped in and about the can D. It is of primary importance to provide a means of a sanitary nature so as to keep the cabinet B in a clean and tidy condition at all times.

The lip 20 is adapted to extend with the 35 cutting edge in an arcuated formation which is desirable as it provides the necessary bulging curve to the ice cream in the disher.

My sanitary frost proof cover is also 40 adapted to be made in the form and construction illustrated in Figures 5 and 6, with a single flaring wall 23 having the bead 24 about the top of the same and the lower band member 25 which carries the 45 lip 20 in the same manner as the collar A illustrated in Figure 1. This form of my collar A is so formed that the band 25 will fit within the upper rim portion 26 of the can D as illustrated in Figure 6.

50 The cover member E may be formed of paper or any other suitable material which preferably is treated to waterproof the same and the ends of the same may be joined together to provide the flaring collar-like formation as illustrated in Figure 7. However, these covers are easily curved and overlapped at the ends to form this shape and will thus fit into the collar A as illustrated in Figure 1, with the ends 27 and 28 of the 55 same overlapping and held in back of the upwardly curved portion of the lip 20 to hold the cover E firmly in place. In other words, the back of the lip 20 functions to hold the sanitary liner E for the cover A.

60 In Figures 1 and 6 I have illustrated the

ordinary cabinet B with the ice in contact with the can D. My collar A is also adaptable to the iceless types of cabinet such as F, illustrated in Figure 8 and in this construction of the cabinet I have illustrated a refrigerating unit G as it is apparent that the refrigerating means in this iceless cabinet F may be of any suitable nature so as to keep the can D cold with the ice cream therein properly froze. 70

I have illustrated another form of my collar A in Figure 8 wherein the flaring portion 23 is formed of a single wall and is provided with a reinforcing bead 24 about the top of the same. This form of my collar A is provided with an annular inwardly extending flange 29 which is formed integral with the side band 25 in this form of my collar A. This inwardly extending flange 29 provides an annular cutting or clearing edge 30 about the inside of the collar A which functions in the same manner as the lip 20 to provide a scraper for the disher so that the merchant may scrape the disher off and dish out the ice cream without having a ragged formation about the edge of the same. In this form of my collar A the sanitary liner E fits within the recess 31 formed between the flange 29 and the flaring wall 23 of the collar A. This recess 31 holds the sanitary liner E firmly in place so that the merchant may keep the inside of the collar A clean and in a tidy condition at all times. 90

The collar A may be made with a flared wall portion 23 offset as illustrated in the plan view in Figure 9 so that the center opening 32 of the collar is offset from the outer diameter of the rim 24. In other words, the opening 32 is not concentric to the rim 24 in the plan illustration in Figure 9. This construction of my collar A is for openings 11 in the cabinets B or F which are off-center to the can D. 100

The nonmetallic waterproof liner C which forms the sanitary cover for the collar A is adapted to provide a frost proofing means over the inner surface of the collar A so that the collar A will not collect frost on the surface thereof, nor will any drippings fall thereon and become froze but will be collected by the replaceable liner E. In this sense the liner E forms a frost resisting means over the surface of the collar A. 110

In accordance with the patent statutes I have described the principles of operation of my invention and while I have illustrated a particular formation and construction of the parts in the drawings, I desire to have it understood that the same is only suggestive of a means of carrying out my invention and that the same may be constructed in other forms and applied to uses other than those above set forth within the 125 130

scope of the following claims without departing from the spirit of my invention.

I claim:

1. A sanitary collar means for ice cream cans and cabinets including, a collar, a flaring collar flange, a straight cylindrical band portion adapted to fit over the ice cream can, and a dead air space formed in said flaring portion.
2. A sanitary frost proof collar for ice cream cabinets including, a band portion adapted to fit the ice cream can, a flaring wall portion projecting above said band, and a replaceable nonmetallic cover for said flaring wall having a moisture resisting nature.
3. A spacer for ice cream cabinets including, a flared portion, a cylindrical band-like portion, and a scraping lip extending from said band and projecting along side thereof to provide a scraper for dishers.
4. A spacer for ice cream cabinets including, a band member, an annular scraping flange projecting upwardly and inwardly from said band portion, and a wall portion adapted to fill the space between the can receiving opening in the cabinet, and to hold the upper end of the ice cream can properly spaced in said cabinet.
5. A spacer collar for ice cream cabinets including, an ice cream can engaging band, an annular scraping flange projecting from said band, and an outwardly flaring wall secured to and extending upward from said band having an annular recess between said band and said wall adapted to receive a sanitary liner in position to cover said flaring wall and to provide a frost resisting surface over said wall.
6. A spacer for ice cream cabinets including, a collar having a band portion, a scraper projecting from said band portion, a flaring wall secured to and projecting from said band portion, and a frost resisting liner adapted to extend over said wall and be held replaceable in relation thereto.
7. A sanitary frost proof collar including, a band portion adapted to engage an ice cream can, a flaring wall adapted to engage an opening in an ice cream cabinet to provide a spacer between the cabinet and the ice cream can to prevent drippings along side of the can, and a sanitary frost proof liner adapted to extend over said flaring wall.

DAVID B. REESE.
